DESIGN FOR A COMBINED BOW AND SIDE COMBS

Lena Karlen, Philadelphia, Pa.

Application April 22, 1941, Serial No. 100,569

Term of patent 7 years

To all whom it may concern:

Be it known that I, Lena Karlen, a citizen of the United States, residing at Philadelphia, in the county of Philadelphia and State of Pennsylvania, have invented a new, original, and ornamental Design for a Combined Bow and Side Combs, of which the following is a specification; reference being had to the accompanying drawing, forming part thereof.

Fig. 1 is a top plan view of a combined bow and side combs, showing my new design.

Fig. 2 is a perspective view thereof as seen from the bottom.

The dominant features of the design reside in the portions shown in full lines.

I claim:

The ornamental design for a combined bow and side combs, substantially as shown and described.

LENA KARLEN.
